LOCK STITCH SEWING MACHINE

George Sauer, Berwyn, Ill., assignor to Union
Special Machine Company, Chicago, Ill., a cor-
poration of Illinois

Application March 19, 1934, Serial No. 716,416

4 Claims. (Cl. 112—220)

The invention relates to new and useful improvements in sewing machines and more particularly to a lock stitch sewing machine, wherein the stitches are formed through the cooperative action of a needle and a rotary hook.

An object of the invention is to provide a machine of the above type wherein the actuated parts of the stitch forming mechanism and the actuated parts of the feeding mechanism are each operated from shafts which terminate in the hollow standard and wherein the rotary hook shaft and the feed actuating shaft are independently connected with a main actuating shaft which operates the needle whereby the number of parts and the lost motion incident to the connecting of the parts, is reduced to a minimum.

A further object of the invention is to provide a machine of the above type wherein the transmitting mechanism is so constructed that the number of intermeshing points between the driving gear and the parts actuated thereby are reduced to a minimum.

In the drawings—

Figure 1 is a view in vertical section through a machine embodying the improvements;

Fig. 2 is a view partly in horizontal section and partly in plan from above the work support, with parts of the work support broken away to show the structure beneath the same, and

Fig. 3 is an end elevation as viewed from the right in Fig. 1, with parts broken away to show the driving mechanism within the hollow standard.

The invention relates to a sewing machine for forming lock stitches. The stitches are produced by a reciprocating needle and a cooperating rotating hook with which is associated a thread carrying bobbin of the usual type. The material is fed across the work support by a feeding mechanism which includes a feed dog carried by a feed bar which is moved endwise for feeding the fabric and which is raised and lowered for producing the feed cycle. The needle bar is operated by the main actuating shaft which extends through a hollow arm overhanging the work support. This arm is carried by a hollow standard. The work support is preferably formed integral with the standard and disposed at a point above the lower end of the standard. As herein shown the standard is closed at its lower end so as to provide an oil sump. The shaft for operating the feeding mechanism extends longitudinally of the work support and through the wall of the hollow standard into the standard. The shaft which operates the rotary hook likewise extends longi-

tudinally of the work support and through the wall of the hollow standard into the standard. There is a transmitting gear in the hollow standard which meshes with a gear on the main actuating shaft which reciprocates the needle bar. There is a gear on the feed shaft which meshes with the transmitting gear and there is likewise a gear on the rotary hook shaft which meshes with the transmitting gear so that the feed actuating shaft and the rotary hook shaft are independently driven from the transmitting gear.

Referring more in detail to the drawings, the invention is shown as applied to a sewing machine which includes a standard 1, which is hollow and which is provided with depending side walls 2 and 3 and end walls which are formed integral therewith, as shown in Fig. 2. The bottom end of the standard is closed by a plate 4, which is attached to the standard so as to provide an oil-tight joint, thus permitting a bath of oil to be maintained at the lower end of the standard. Formed integral with this standard is a supporting bed or work support 5. This work support 5 is connected to the standard at a point above the lower end thereof or it may be said that the standard has a portion which extends below the work support. The standard is hollow and supports an arm 6 which overhangs the work support. The arm forms an extension of the hollow standard.

At the outer end of the overhanging arm is a needle head 7, in which a needle bar 8 reciprocates. Said needle bar carries a needle 9. Extending through the overhanging arm is the main actuating shaft 10 which is mounted in a bearing 11 at its outer end and in a bearing 12 at the standard end thereof. At the outer end of this shaft 10 is a crank disk 13 carrying a crank which is connected to the link 14, and the link 14 is in turn connected to the needle bar. Thus it is that the rotation of the shaft 10 will reciprocate the needle bar.

Located beneath the work support and cooperating with the needle is a rotary hook 15 carried by a shaft 16. The shaft 16 rotates in a bushing 17 mounted in a bearing lug 18. This shaft also rotates in a bushing 19 in the wall 2 of the hollow standard.

The fabric is fed across the work support by a feed dog 20 carried by a feed bar 21, which is pivoted to a feed rocker 22. The feed bar is given its back and forth movements and also its up and down movements for imparting feed cycles to the feed dog by a shaft 23. This shaft 23 is mounted for rotation in a bushing carried by the

depending lug 18 and also in a bushing 31 carried by the inner wall 2 of the standard. On the shaft 23 is an eccentric, with which an eccentric strap 24 cooperates. The eccentric strap 24 carries a rod 25 which has a telescoping engagement with a sleeve 26, which sleeve in turn is pivotally connected to the feed rocker. Attached to the sleeve 26 is a link 27 which is mounted for oscillation on an arm 28 carried by a shaft 29 which is capable of adjustment to different set positions. As the eccentric rotates, it will impart a sliding movement of the rod into and out of the sleeve, which is an idle movement and it will also impart a lateral movement to the sleeve 26. The lateral movements of the sleeve 26 through the link 27, are converted into an endwise movement of the arm 26 and this is what moves the feed bar back and forth. The feed bar is raised and lowered by an eccentric strap 30 cooperating with an eccentric on the end of the shaft 23 and connected in the usual manner to the feed bar. This feed-ing mechanism forms no part of the present in-vention, but is shown and described in the appli-cation filed by George Sauer and Clarence C. Smith, on May 31, 1933, Serial No. 673,738.

The shaft 16 extends through an opening into the hollow standard and the bushing 19 closes the opening. The shaft 23 also extends through an opening in the standard and the bushing 31 closes this opening so that the lower end of the standard is completely closed and the ends of the two shafts 16 and 23 projecting into the hollow stand-ard. At the end of the shaft 23 within the standard, is a gear 32. This gear meshes with a gear 33 having a hub 34 which is mounted for rotation on a fixed shaft 35. There are collars 36, 36 fixed to the shaft and located at each side of the hub for maintaining the rotating position of the gear 33 thereon. On the main actuating shaft 10 is a gear 37 which is fixed to the shaft and which meshes with this transmitting gear 33. As the main actuating shaft rotates, it will through these intermeshing gears impart a rotation to the feed shaft and thus the feed dog is given its feeding movements through this single shaft and the gearing connection with the main actuating shaft. The gears 32 and 37 are so di-mensioned that the main actuating shaft and the feed shaft rotate in the same timing and 50 impart a feeding movement to the fabric for each stitch formation.

Mounted on the end of the shaft 16, which projects into the hollow standard, is a gear 38. This gear 38 is located so that it overlaps in part the gear 32. The transmitting gear 33 is of sufficient width so that both the gears 32 and 38 mesh therewith. One reason for placing these gears 32 and 38 so that they overlap in part, is to bring the shafts 18 and 23 relatively close together. The 60 rotary hook shaft has its longitudinal axis lying in a vertical plane containing the path of recipro-cation of the needle and the feed shaft has its axis lying in a vertical plane slightly in rear of the stitching point and at the most advantageous position for lifting the feed bar. Another reason for placing the gears 32 and 38 so that they over-lap in part, is to bring said gears into mesh with a different section of the teeth on the transmitting gear. It is particularly essential that the rotations 70 of the hook relative to the reciprocations of the needle be maintained so that a hook will pass the needle at the exact point in its path of recipro-cation in order to take the needle, thread loop therefrom. There is very much less strain on the driving gears for the rotary hook than on the

driving gears for the feed, as the feed dog which moves intermittently, at one part in its cycle, not only moves the fabric, but it lifts the farbic off from the work support against the heavy tension of the spring on the presser foot. During its re-turn cycle, the feed dog is free from these strains, and therefore, the strain on the feed shaft is an intermittent strain, causing greater wear on the teeth of the gear carried by the feed shaft. While possibly the wear on the teeth of the transmitting gear, through its contact with the actuating gear, is substantially uniform, the wear on the portions of the teeth which contact with and operate the hook, will be less than on the gear which operates the feed, and when the rotary hook has a direct geared connection with the needle actuating shaft, which is independent of the feed, a better timing is maintained. Furthermore, the trans-mitting gear is provided with a number of teeth which is not a multiple of the teeth in the gears with which it meshes, so that there is a progres-sive shifting movement whereby the tooth or teeth in either gear 32, 37 or 38 which is subject to the special strain, will find itself in contact suc-cessively with a different tooth in a transmitting gear. A still more effective distribution of wear is obtained by making the material of the teeth of the transmitting gear softer, than the material of the teeth of the other gears, as for example, of bakelite. The greatest wear will be taken by the transmitting gear and thus will be distributed on all of the teeth. This arrangement of the teeth in the driving train of gears, and the general type of machine to which this invention is applied, is shown and described more fully in the application 35 of Norman V. Christensen and Charles F. Rubel, filed May 9, 1933, Serial No. 670,186.

The gear 38 is so dimensioned that the rotary hook shaft will be given two rotations for each rotation of the feed shaft. The gear 32 rotates 40 in a position well down toward the lower end of the standard. The oil sump at the lower end of the standard is filled with oil, so that the lower portion of this gear 32 extends beneath the surface of the bath of oil. This will hand up 45 the lubricating oil onto the gear 33 and the gear 37 and in turn the gear 38 will also be lubricated. While the invention is described as embodied in a sewing machine having a hollow enclosed standard, with an oil sump for lubricating the 50 intermeshing gears, it will be understood that from certain aspects of the invention, the driv-ing mechanism for the needle, the feed and the looper, which is shown and described, may be used in other types of machines. It is also ob-55 vious that minor changes in the details of con-struction may be made without departing from the spirit of the invention as set forth in the ap-pended claims.

Having thus described the invention, what I 60 claim as new and desire to secure by Letters-Patent, is—

1. A sewing machine including in combination, a standard, a work support, an arm overhanging the work support, a needle bar carried by said arm, a feeding mechanism and a rotary hook be-65neath the work support, a transmitting gear car-ried by the standard, an actuating shaft for the needle bar geared to the transmitting gear, an-70 other actuating shaft for the feeding mechanism directly geared to the transmitting gear, and another actuating shaft for the rotary hook di-rectly and independently geared to the transmit-ting gear.

2. A sewing machine including in combination, 75

5 a standard, a work support, an arm overhanging the work support, a needle bar carried by said arm, an actuating shaft carried by said arm and connected to said needle bar, a feeding mechanism and a rotary hook beneath the work support, a transmitting gear carried by the standard, a gear on the actuating shaft for the needle bar meshing with said transmitting gear, an actuating shaft for the feeding mechanism, a gear 10 carried by said shaft in said standard and meshing with said transmitting gear, an actuating shaft for the rotary hook, a gear carried by said last-named actuating shaft in the standard and directly meshing with the transmitting gear, said 15 transmitting gear having a width slightly greater than the combined width of the gear actuating the feed shaft and the gear actuating the rotary hook, said gears actuating the feed shafts and the rotary hook being disposed so as to mesh with 20 different sections of the teeth of the transmitting gear.

3. A sewing machine including in combination a hollow standard closed at its lower end, a work support connected thereto and disposed above 25 the lower end of the standard, an arm carried by the standard and overhanging said work support, a needle bar mounted for reciprocation on said arm, an actuating shaft for the needle bar mounted on said arm and extending into said 30 standard, a feeding mechanism beneath the work support, an actuating shaft therefor disposed beneath the work support and extending into said hollow standard, a rotary hook beneath the work support, an actuating shaft therefor extending into said hollow standard, a gear carried by said last-named shaft in said standard and meshing with said transmitting gear whereby said rotary hook shaft is operated independently of the feed shaft from said transmitting gear.

the work support, an actuating shaft therefor extending into said hollow standard, means located within the hollow standard and having operative connection with the actuating shaft in the overhanging arm and having independent operating connections respectively with the feed operating shaft and the rotating hook operating shaft for actuating the same.

4. A sewing machine including in combination a hollow standard closed at its lower end, a work support connected thereto and disposed above the lower end of the standard, an arm carried by the standard and overhanging said work support, a needle bar mounted for reciprocation on said arm, an actuating shaft for the needle bar 10 mounted on said arm and extending into said standard, a gear mounted on said actuating shaft in said hollow standard, a transmitting gear mounted in said hollow standard and meshing with said gear on the actuating shaft, a feeding 15 mechanism beneath the work support, an actuating shaft therefor disposed beneath the work support and extending into the hollow standard, a gear carried by said shaft in said standard meshing with said transmitting gear, a rotary 20 hook beneath the work support, an actuating shaft therefor extending into said hollow standard, a gear carried by said last-named shaft in said standard and meshing with said transmitting gear whereby said rotary hook shaft is operated 25 independently of the feed shaft from said transmitting gear.

GEORGE SAUER.
